MORRIS ISAACSON, OF BROOKLYN, NEW YORK.

DIE AND PRESS FOR ATTACHING WOOD HEELS.

1,216,999.

Specification of Letters Patent. Patented Feb. 20, 1917.

Application filed May 23, 1916. Serial No. 99,273.

To all whom it may concern:

Be it known that I, MORRIS ISAACSON, a citizen of the United States, and a resident of the city of New York, borough of Brooklyn, in the county of Kings and State of New York, have invented a new and Improved Die and Press for Attaching Wood Heels, of which the following is a full, clear, and exact description.

10 This invention relates to shoe making machines and particularly to an improved die and press for preparing the heel seat portion of shoes to receive heels in such manner as to produce an accurate fit at the juncture of the heel with the remaining part of the shoe.

Another object of the invention is to provide an improved die for pressing the part of the shoe which receives the heel into the 20 correct shape for receiving the heel.

In the accompanying drawings:-

Figure 1 is a side view of a press and associated parts embodying the invention, certain members being broken away for better illustrating the construction.

Fig. 2 is a fragmentary sectional view through Fig. 1 on line 2—2.

Fig. 3 is a fragmentary sectional view through Fig. 1 on line 3—3.

30 Fig. 4 is a detail sectional view through Fig. 3 on line 4—4.

Fig. 5 is a transverse sectional view through Fig. 4 on line 5—5.

Fig. 6 is a bottom plan view of the die 35 used in forming a heel seat on the heel portion of a shoe.

Fig. 7 is a fragmentary side view of a shoe with a slightly modified form of die applied to the heel seat portion thereof.

40 Referring to the accompanying drawings by numerals, 1 indicates a base to which are secured posts or uprights 2 and 3, the same being held in place by nuts 4 engaging suitable reduced threaded extensions of the

45 posts. Connected with the upper end of the posts 2 and 3 or formed integral therewith is a cross bar 5 through which the threaded bar 6 extends, the aperture accommodating bar 6 being also threaded so that when the

50 bar is rotated by the handle 7 the foot 8 is forced downwardly or upwardly according to the direction of rotation. The foot 8 is universally journaled on the bar 6 by a suitable ball and socket connection 9 so that the 55 foot can accommodate itself to the particular angle of the upper surface of the die.

It will be noted that the foot 8 is soldered to or formed integral with the cross bar 8', which cross bar is notched at each end so as to partially surround the posts 2 and 3 in 60 order to be guided thereby in its upward and downward movement.

The die 10 as shown in Figs. 1, 2 and 6 is preferably formed with a solid body portion 11 and a border member 12 which is rigidly 65 secured to the body 11 by any suitable means, as for instance, screws 13. The bottom of the die 10 is formed in any shape desired and so is the lower edge of the member 12, the shape of these parts being the negative of the shape of a heel section of a shoe which has been pressed thereby. As shown in Figs. 1 and 2, a small depression or groove is provided between the body 11 and member 12 into which part of the upper of 70 the shoe is crowded when the die is pressed tightly against the heel portion of the shoe. This causes a distinct curved or side section 17 to be produced and assists in holding the heel in place when positioned thereon as 75 well as causing a better finish to be presented. The idea is to press the heel section of the shoe as shown in Fig. 1 so that the same will conform in all its details to the shape of a wooden heel to be applied later. 80 For the purpose of identification a plurality of pins 15 forming a number as shown in Fig. 6 are arranged in the die 10 and punches or depresses part of the sole leather forming the heel section of the shoe. The 85 die is preferably so arranged as to press the heel section of the shoe in order to produce a central surface 16 and a curved or side section 17. The wooden heel to be applied is made of such a shape as to exactly fit 90 these two surfaces and when an adhesive has been placed on the heel and the heel pressed tightly against the surfaces 16 and 17 a proper connection between the two parts is 95 secured.

100 While the shoe 19 is being operated on by the die 10 the heel end of the last is supported by a post 20 provided with a notched-out or cutaway portion 21 for accommodating the spring 22 pivotally mounted at 23. An auxiliary spring 24 is riveted or rigidly secured in any suitable manner at 25 so that spring 22 will be properly supported and, consequently, support the outer end of the shoe 19 in a horizontal position. In order to accommodate the 105 spring 22 and associated parts to shoes of 110

different sizes and shapes the supporting fork 26 is adjustably clamped in position by a thumb screw 27, as shown more particularly in Figs. 4 and 5. It will be observed that fork 26 is provided with a body 28 folded around the upper end of the spring 22 so as to readily slide thereover, said spring being provided with a slot 29 for accommodating the screw 27. A suitable rubber or other covering 30 is provided on the fork 26 for preventing scarring of the shoe.

The standard 20 is held against lateral movement by the guides 31 and 31' but is not prevented from sliding out from beneath the presser foot 8 when said foot has been released. This allows the shoe to be released by only part of a turn of the screw 6 and the shoe may then be readily pulled out, the standard 20 sliding between the guides 31 and 31'. A new shoe may be substituted while the standard 20 is in its outer position and then the shoe and standard 20 may be moved back to the position shown in Fig. 1. In regard to the pins 15 in die 10 these are used to identify the particular shoe with the particular heel to be used. Any heel having the same number as is provided by the pins 15 may be placed on shoe 19 after the die has been removed and when so placed will correctly fit the seat produced by the die.

In forming the standards or uprights 2 and 3 and cross bar 5, together with member 6 and associated parts, it is aimed to construct these parts comparatively strong in order that a considerable pressure may be exerted on the shoe for producing or pressing a seat in which the heel is placed. A certain shaped die 10 has been disclosed in the drawing but it is evident that other shapes may be used according to the style of shoe and heel without departing from the spirit of the invention. It is also evident that other slight modified forms may be used without departing from the spirit of the invention provided means are presented which will press a seat into the shoe.

In constructing heels the same are formed in several ways in order to produce what is known as orthopedic, Louis or plain heels. In Fig. 7 a different form of die is shown to that shown in Fig. 6 so as to disclose how the device is applicable to heels of any design or shape. As shown in Fig. 7, the die 10' is provided with a pointed end 55 which will press or cut the sole leather at 56 unless the sole leather has been previously cut and trimmed. This pressing or cutting the sole of the shoe at 56 is to allow the heel to fit properly against the heel seat and the sole so as to make a neatly fitting construction. In forming the heel seat the same may be pressed completely by the die 65 or may be trimmed with a knife, said trim-

ming extending around the heel portion of the shoe from one cut 56 to the opposite cut 56, and after such cutting operation the die may be forced into position to shape up the parts. Also, an extension 58 is provided which slants gradually upward as shown in Fig. 7 so as to give a less and less pressure and thereby cause a gradual slant of the sole from the point where no pressure is provided to a seat which is pressed firmly in the desired shape. This will prevent the sole 57 from bulging or bowing upwardly and adjacent the heel as the same is pressed on an incline and thereby produces a continuous even appearing sole and heel portion for receiving a wood heel.

In arranging the member 12 in position it is intended that the counter shall be pressed so that when the heel is placed in position a good fit may be produced and a smooth pleasing appearance disclosed.

What I claim is:

1. In a device of the character described, a support for the heel end of a shoe, a die constructed and arranged to engage and shape the heel seat portion of the shoe on said support, and a pressing member for forcing said die against said heel seat portion so as to shape a heel seat thereon. 90

2. In a device of the character described, a support for the heel portion of a shoe, a die constructed and arranged to engage and shape the heel seat portion of the shoe on said support, and a rotatable pressing member for forcing said die against said heel seat portion so as to shape a heel seat thereon. 100

3. In a device of the character described, a support for the heel portion of a shoe, a resilient member for supporting and guiding the toe of the shoe arranged on said support, a die constructed and arranged to engage and shape the heel seat portion of the shoe on said support, a rotatable pressing member for forcing said die against said heel seat portion so as to shape the heel seat thereon, and means for holding said pressing member in proper position for acting on said die. 105

4. In a device of the character described, a support for the heel portion of a shoe, a resilient supporting member for the toe of the shoe, a die, and means for forcing said die against the heel portion of said shoe so as to shape a heel seat thereon, said die operating substantially opposite said support. 120

5. In a device of the character described, a support for the heel portion of a shoe, a base for holding said support against lateral movement, an upright extending from said base, a transverse bar extending from said upright, a traveling member associated with said upright, said traveling member acting as a presser member, and a die constructed 125

and arranged to engage and shape the heel seat portion of the shoe on said support interposed between said traveling member and the heel portion of said shoe whereby when 5 said traveling member is moved in one direction the die will press said heel portion so as to shape a heel seat thereon.

6. In a device of the character described, a support for the heel portion of a shoe, a 10 die constructed and arranged to engage and shape the heel seat portion of the shoe on said support, said die being provided with projections forming a number of identification marks, and a pressing member for forcing 15 said die against said heel seat portion so as to shape a heel seat thereon.

7. In a device of the character described, a die for forming a heel seat on a shoe, said die comprising a body for producing a seat 20 when pressed against the heel portion of a shoe, and an encircling member formed with a round portion arranged to press the counter of the shoe in order to cause a nicely appearing finish when the heel is placed in position.

8. In a device of the character described, a die constructed to shape a heel seat on the heel portion of a shoe, said die being formed with a body for shaping a heel seat when forced against the heel portion of a shoe, a 30 rounded portion, and a groove positioned between the rounded portion and the body.

9. In a device of the character described, a die constructed to shape the heel seat on the heel portion of a shoe, said die being 35 formed with a projecting point for pressing or cutting the sole in front of the heel portion of said shoe.

10. In a device of the character described, a die constructed to shape the heel seat on 40 the heel portion of a shoe, said die being formed with a body and an encircling portion for producing a side section, said die being also formed with a projecting point for pressing or cutting across the width of 45 the sole in front of the heel portion of said shoe, and a slanting extension for pressing the sole adjacent the heel portion of said shoe.

MORRIS ISAACSON.
